UNITED STATES PATENT OFFICE

ERNST SCHEBERA, OF DETROIT, AND HARRY A. SHAW, OF HUNTINGTON WOODS, MICHIGAN, ASSIGNORS TO TERNSTEDT MANUFACTURING COMPANY, OF DETROIT, MICHIGAN, A CORPORATION OF MICHIGAN

DESIGN FOR AN OUTSIDE DOOR HANDLE OR SIMILAR ARTICLE FOR AN AUTOMOTIVE VEHICLE

Application filed February 27, 1933. Serial No. 47,344. Term of patent 7 years.

To all whom it may concern:

Be it known that I, ERNST SCHEBERA, a citizen of the United States, residing at 1295 Balmoral Drive, Detroit, in the county of Wayne and State of Michigan, and I, HARRY A. SHAW, a citizen of the United States, residing at 26725 Hendrie Avenue, Huntington Woods, in the county of Oakland and State of Michigan, have invented a new, original, and ornamental Design for an Outside Door Handle or Similar Article for an Automotive Vehicle, of which the following is a specification, reference being made to the accompanying drawing forming part thereof.

Fig. 1 is a front elevation.

Fig. 2 is a plan view.

Figs. 3 and 4 are sectional views along the lines 3—3 and 4—4 respectively of Fig. 2.

We claim:

The ornamental design for an outside door handle or similar article for an automotive vehicle substantially as shown.

ERNST SCHEBERA.
HARRY A. SHAW.
